Int. Cl. D25—02; D23—99

U.S. Cl. D54—2 A

FIG. 1 is a front elevational view of a grille showing my new design;

FIG. 2 is a top plan view thereof; and

FIG. 3 is a cross-sectional view taken on line 3—3 of FIG. 3.

The grille is broken away in FIGS. 1 and 3 to indicate indeterminate length.

This is a division of design application Ser. No. D. 21,753, filed Mar. 5, 1970, and now Pat. No. D. 222,895.

We claim:

The ornamental design for a grille, as shown.
